UNITED STATES PATENT OFFICE

FRANK M. FINLAYSON, OF WORCESTER, MASSACHUSETTS

CABLE CLAMP

Application filed August 6, 1930. Serial No. 473,457.

This invention relates to a clamp by which a rope, wire or cable may be firmly anchored or secured.

It is the general object of my invention to provide a clamp for such purposes so constructed that a cable may be firmly secured therein and will be securely held from accidental displacement, while it may at the same time be readily removed or released when desired.

Special features of my invention relate to the provision of simple and relatively inexpensive parts, easily assembled and particularly well adapted to the designed purpose.

My invention further relates to arrangements and combinations of parts which will be hereinafter described and more particularly pointed out in the appended claims.

Preferred forms of the invention are shown in the drawings, in which

Fig. 1 is a side elevation of one form of my improved clamp;

Fig. 2 is an end view thereof, looking in the direction of the arrow 2 in Fig. 1;

Fig. 3 is a sectional side elevation of the clamp shown in Fig. 1;

Fig. 4 is a bottom view of the clamping member;

Fig. 5 is a detail sectional view, taken along the line 5—5 in Fig. 1;

Figs. 6, 7 and 8 are diagrammatic views indicating the manner in which the clamping member may be assembled with or removed from the frame member;

Fig. 9 is a sectional side elevation showing a slight modification of my invention, and

Fig. 10 is a sectional side elevation showing an additional slight modification.

Referring to the drawings, my improved cable clamp comprises a frame member 20 and a clamping member 21. The frame member 20 is preferably formed from a single piece of heavy sheet metal, bent to a U-shaped section as indicated in Fig. 2 and having the side portions thereof extending upwardly and spaced apart in parallel relation. The clamping member 21 is provided with a serrated eccentric clamping face 24 and with lateral projections 25 upon which

the clamping member is pivotally supported in openings 26 in the side portions of the frame member 20.

In one form of the invention, the frame member is depressed at the bottom to receive an attaching member 30 which extends through an opening 31 in the bottom of the frame member and which may be secured in said opening by a nut 32 threaded on the shank 33 of the member 30.

The enlarged inner end of the member 30 is preferably concaved, as indicated at 34, to correspond with the curvature of the clamping member 21. The threaded shank 33 of the member 30 may be extended downward, as indicated in Fig. 1, for attachment to a trolley wire T or for any other purpose.

The sides of the clamping member 21 are preferably grooved, as indicated at 36 (Figs. 3 and 5), and spring pawls 38 are struck up from the sides of the frame member 20, the struck-up portions being beveled or pointed and being bent and displaced so that the points will project inward, as indicated in Fig. 5, so as to engage the grooves 36 in the clamping member 21. The frame member 20 is preferably provided with openings 40 at each end to which suspension wires or other devices may be attached.

When a wire or cable W is to be secured in the clamp, the wire is inserted as indicated in Figs. 1 and 3, the clamping device 21 is swung downward into engagement with the wire, and a sharp blow is delivered against the upwardly extending end of the clamping member 21, such blow being in the direction of the arrow a in Fig. 3.

A blow in this direction advances the member 21 to clamping position and during such movement the prongs or spring pawls 38 engage successive grooves 36 in the member 21 and prevent reverse movement thereof. The cable is thus securely clamped and will remain thus clamped even though tension on the cable is relieved. If, however, it is desired to release the cable, the spring pawls 38 may be sprung outward by inserting a tool thereunder, after which the clamping member may be reversely moved.

The openings 26 in the side portions of the

frame member 20 are elongated, as indicated at 43 and 44 in Fig. 6, these elongated portions being disposed in opposite directions relative to the axis of the clamping member 21.

5 The parts may be assembled by inverting the member 21, as indicated in Fig. 8, and inserting the pivot portions 25 between the side portions of the frame member 20 as shown in Fig. 7. When the member 21 is thus inserted it may be rotated 90° to the position shown in Fig. 6. It can then be swung downward to the position shown in Fig. 3 and upon engagement with a wire or cable 10 W the pivot portions 25 will be raised into the slightly offset bearing openings 26 which will determine the pivoted axis for angular movement thereof.

15 The extreme end portions of the parts 25 are preferably enlarged, as indicated at 47, (Figs. 2 and 7) and these enlarged end portions are positioned outside of the side portions of the frame member 20 when the parts 20 are in operative relation and prevent spreading of the sides under pressure.

25 In Fig. 9 I have indicated a slight simplification of my invention, in which the frame member 50 is formed with a straight bottom portion 51 and the parts are so proportioned that the attaching member 30 may be omitted.

30 In Fig. 10 I have indicated the use of a wedge 52, transversely concave and smooth on its under face to fit the upper surface of a lead-covered cable C and concave longitudinally on its upper face, as indicated at 54, to receive the eccentric face of the clamping member 21.

35 I have thus provided an extremely simple cable clamp which, in its essential details, comprises only two parts, the frame member 20 and the clamping member 21, the use of the attaching member 30 being optional.

40 The spring pawls 38 are formed integral with the frame member 20, and the grooves 36 and pivot portions 25 are formed integral with the clamping member 21. The parts 45 are readily assembled or separated without the use of any tools and are readily secured in position by a simple blow from a hammer or other suitable tool.

50 Having thus described my invention and the advantages thereof, I do not wish to be limited to the details herein disclosed, otherwise than as set forth in the claims, but what I claim is:—

55 1. A cable clamp comprising a frame member, an eccentric clamping member pivotally mounted therein, and cooperating locking devices on said frame and clamping member effective to prevent unlocking movement of said clamping member until said locking devices are manually rendered inoperative.

60 2. A cable clamp comprising a U-shaped sheet metal frame member, an eccentric clamping member pivotally mounted there-

65 in, and cooperating locking devices on said frame and clamping member effective to prevent unlocking movement of said clamping member until said locking devices are manually rendered inoperative.

70 3. A cable clamp comprising a sheet metal frame member, a clamping member pivotally mounted therein, and cooperating locking devices on said frame and clamping members, parts of said locking devices being formed integral with said sheet metal frame member.

75 4. A cable clamp comprising a frame member having inwardly projecting spring pawls, and a clamping member pivotally mounted in said frame member and having grooves in its side faces positioned for engagement by said pawls.

80 5. A cable clamp comprising a frame member having inwardly projecting spring pawls formed integral therewith, and a clamping member pivotally mounted in said frame member and having grooves in its side faces positioned for engagement by said pawls.

85 6. A cable clamp comprising a one-piece frame member having spaced side portions, and a clamping member pivotally mounted therein, said clamping member being readily inserted and removed as a unit from said frame member.

90 7. A cable clamp comprising a frame member having spaced side portions, and a clamping member pivotally mounted therein, said clamping member being readily inserted and removed as a unit from said frame member and having provision to prevent spreading of said portions when in use.

100 8. A cable clamp comprising a frame member having spaced side portions, and a clamping member pivotally mounted therein, said clamping member having cylindrical lateral projections and said side portions having aligned openings, said openings being elongated in opposite directions from the axis of said clamping member to permit insertion of said member by a turning movement thereof.

105 9. The combination in a cable clamp as set forth in claim 8, in which the outer ends of said lateral projections are enlarged to prevent spreading of said side portions when in use.

110 10. A cable clamp comprising a U-shaped frame member, a clamping member pivotally mounted between the sides of said frame member, said member having a depressed bottom portion with an opening therethrough, and an attaching member secured in said opening and extending outward therefrom.

115 11. The combination in a cable clamp as set forth in claim 10 in which said attaching member has an enlarged head adapted to

support a cable against the passage of said clamp.

12. The combination in a cable clamp as set forth in claim 10 in which said attaching member has an enlarged head adapted to support a cable against the pressure of said clamp, said head being concaved to correspond to the shape of the clamping member.

13. A cable clamp comprising a U-shaped frame member, a clamping member pivotally mounted between the sides of said frame member, and a wedge shaped member insertable between a cable and the face of the clamping member, said wedge-shaped member being concaved transversely on its lower face to fit the cable and being concaved longitudinally on its upper face to conform to the curvature of the clamping face of said clamping member.

14. In testimony whereof I have hereunto affixed my signature.

FRANK M. FINLAYSON.
